Des. 178,695
Patented Sept. 4, 1956

178,695

ROAD LINE MARKER

George T. Robbins, Tuscumbia, Ala., assignor to Robbins
Floor Products, Inc., Tuscumbia, Ala., a corporation of
Alabama

Application February 27, 1956, Serial No. 40,330

Term of patent 14 years

(Cl. D72—1)

Fig. 1 is a top perspective view of a road line marker showing my new design;

Fig. 2 is a bottom perspective view thereof;

Fig. 3 is a side elevational view thereof;

Fig. 4 is a front elevational view thereof; and

Fig. 5 is an enlarged detail of the bottom surface of the road line marker design.

I claim:

The ornamental design for a road line marker, as shown.
